EMBROIDERY HOOP

Filed March 19, 1928

UNITED STATES PATENT OFFICE

TRUMAN L. ATKINSON, OF LUDINGTON, MICHIGAN

EMBROIDERY HOOP

Application filed March 19, 1928. Serial No. 262,963.

This invention relates to embroidery hoops and is primarily concerned with a simple and novel construction of embroidery hoop whereby the meeting end portions of the hoop, 5 one at each side of the parting therein, are properly guided with respect to each other by a very simple construction which reduces the cost of manufacture and at the same time provides a particularly useful and advantageous structure for manufacture and assembly.

An understanding of the invention for the attainment of the ends stated may be had from the following description taken in connection with the accompanying drawing, in which,

Fig. 1 is an elevation illustrating the invention as applied at the end portions of the hoop at each side of the parting therein.

Fig. 2 is a fragmentary longitudinal section therethrough.

Fig. 3 is a transverse vertical section through the hoop adjacent one end thereof.

Fig. 4 is an inner elevation showing the invention applied to a cork lined hoop.

Fig. 5 is a fragmentary longitudinal section therethrough, and

Fig. 6 is a transverse section through the hoop shown in Fig. 4 near one end thereof.

Like reference characters refer to like parts in the different figures of the drawing.

The embroidery hoop is made of sheet metal in circular form and includes a flat web 1 at each edge of which, in the form shown in Figs. 1 to 3 inclusive, the metal is formed into outwardly turned rolls 2 entirely around the length of the hoop. Short portions 3 of the rolls at the respective ends of the hoop having their inner edges cut away to provide 40 for the insertion of a plate 4 hereafter described.

A plate 4 of flat metal of the form best shown in Fig. 1 is located between the channel guides 3 of both ends of the loop and 45 extends across and bridges the gap or parting therein. The side edges 4^a of the plate are turned upwardly and enter the channel guides 3, as shown in Fig. 3, while the ends of the plate are substantially of U-form, there being provided by this construction a very secure

and firm connection between the ends of the ring, yet one which permits a free sliding movement of the plate with respect to the ring ends or vice versa.

Any practical means may be used for drawing the ends of the hoop toward each other. In the form shown in Figs. 1 to 3 inclusive, loops 5 are struck outwardly from the webs 1 adjacent each end of the plate 4 and a coiled spring 6 under tension is connected at 60 each end with said loops, the tendency of the spring being to draw the two ends of the hoop toward each other. It is evident, however, that the ends of the hoop may be spread apart readily by exerting force sufficient to stretch the spring, but that as soon as the force is released the spring will draw the ends of the hoop toward each other and contract the hoop against work located within it.

In Figs. 4 to 6 inclusive, an application of the invention to a different form of hoop is shown. In this case the rolls 2 and the channel guides 3 are turned inwardly instead of outwardly, as in the construction first described, and the bridging plate 4 is located at the inner side of the web instead of the outer side. The hoop is lined with a cork lining 7 which at its ends is reduced in thickness, as indicated at 7^a, the amount of reduction being equal to the thickness of the plate 4.

In this form of the application of the invention there is shown a different manner of drawing the ends of the hoop toward each other. Brackets 8 are attached to the outer sides of the web 1 a distance from each end of the hoop which extend outwardly for a short distance and are then turned toward each other and terminate in oppositely screw threaded shanks 9. A turn buckle 10 is located between and connected with the shanks 9. Turning the turn buckle serves to either draw the ends of the hoop toward each other or separate them in accordance with the direction in which the turn buckle is operated.

It is evident that with this construction the hoop ends are of identical form. It is not necessary to make one of a form to telescope within the other as has been very com-

mon practice heretofore, but by making the ends of the hoop of the same form a reduction in the manufacturing cost is had due to less number of operations, less handling of the materials and a less number of tools and dies for manufacturing. The bridging plate 4 is a very simple element to produce and is assembled by merely inserting the ends thereof between the side guide channels 3.

10 The bridging plate 4 not only serves to keep the ends of the hoop in alinement and properly guide the same in their movements toward or away from each other but also insures that the material held within the hoop shall not bunch up and extend through the gap or parting in said hoop. This construction of embroidery hoop has proved very satisfactory in service. The invention is defined in the appended claims and is to be considered 20 comprehensive of all forms of structure coming within their scope.

I claim:

1. A parted embroidery hoop of metal having a flat web and rolled edges, a bridging plate of flat metal located between said rolled edges and relatively movable with respect to both ends of the hoop bridging the gap between the ends of said hoop, and means for drawing the ends of said hoop toward each 30 other.

2. An embroidery hoop of metal having a parting at one side therein and formed with guides at its side edges at each side of the parting, means attached to the hoop at a distance from each end thereof for drawing the ends together and a rectangular plate of flat metal located between the guides and between the attachments of said means bridging the gap between adjacent ends of the hoop at said 40 parting, said plate being movable relative to both ends of the hoop.

3. An embroidery hoop having a parting therein at one side, said hoop being formed with return bent guides at its edges, a flat bridging plate extending across said parting from one end of the hoop to the other, having its edges curved away from the plane of the plate and received in said guides, and means for drawing the ends of the hoop toward each 50 other.

In testimony whereof I affix my signature.

TRUMAN L. ATKINSON,
